US0D1063822S

(12) **United States Design Patent** (10) **Patent No.:** **US D1,063,822 S**
(45) **Date of Patent:** **** Feb. 25, 2025**

(54) **POWER BANK**

(71) Applicant: **Qing Lai**, Shenzhen (CN)

(72) Inventor: **Qing Lai**, Shenzhen (CN)

(**) Term: **15 Years**

(21) Appl. No.: **29/889,776**

(22) Filed: **Apr. 17, 2023**

(30) **Foreign Application Priority Data**

Dec. 15, 2022 (CN) 202230840294.4

(57) **CLAIM**

The ornamental design for a power bank as shown and described.

DESCRIPTION

FIG. 1 is a perspective view of a power bank showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines in the drawings depict portions of the power bank that form no part of the claimed design.

1 Claim, 8 Drawing Sheets
